CIRCUIT BREAKER

Robert C. Dickinson, Wilkinsburg, William H. Stuellein, East McKeesport, and Fritz E. Florschutz, Wilkinsburg, Pa., assignors to Westinghouse Electric Corporation, East Pittsburgh, Pa., a corporation of Pennsylvania

Application September 15, 1942, Serial No. 458,358

18 Claims. (Cl. 200—89)

1

This invention relates to circuit breakers and more particularly to a high-speed circuit breaker which is operated to automatically interrupt the circuit as a result of reversal of the current in the circuit controlled by the breaker.

An object of the invention is the provision of an improved circuit breaker which is operated at high speed to open the contacts and in which the contacts are trip free of the closing means.

Another object of the invention is to provide an improved circuit breaker in which the support frame for the breaker mechanism forms a part of the magnetic circuit for the holding magnet.

Another object of the invention is to provide a circuit breaker with an improved trip mechanism wherein a trip magnet core member forms a part of the magnetic circuit for a separately energized holding coil.

Another object of the invention is to provide a circuit breaker of improved construction which is safe and reliable in operation, and inexpensive to manufacture.

Another object of the invention is to provide an improved circuit breaker wherein a pivoted contact member is held in closed position by a latch member pivoted eccentrically of the contact member pivot and movable substantially radially to said pivot to release the contact member.

Another object of the invention is to provide an improved circuit breaker with a novel latch member which is movable longitudinally of itself to release a contact member and which is rotatable and longitudinally movable to reset position.

Another object of the invention is to provide a circuit breaker with an improved latch structure wherein a latch member which releasably connects a switch member to an operating member is longitudinally movable to disconnect the switch member from the operating member and wherein the latch member is rotatably and longitudinally movable to reconnect said switch member to the operating member.

Another object of the invention is to provide an improved operating mechanism for a circuit breaker wherein a latch is movable by a trip device to effect opening of the contacts, the latch being movable by the operating mechanism to close the contacts.

Another object of the invention is the provision of an improved operating mechanism for a circuit breaker wherein a latch is operable by a trip device to effect opening of the breaker irrespective of the position of the operating mecha-

2

nism, said latch being operable by the operating mechanism to close the breaker.

Another object of the invention is the provision of an improved circuit breaker operating mechanism wherein the circuit breaker is held latched in closed position by a holding magnet which acts to hold a latch in a position to connect the movable switch member to an operating member, the latch being operable by a relatively small component of the opening bias of the breaker to release the switch member upon a predetermined reduction of the magnetic flux.

The novel features that are considered characteristic of the invention are set forth in particular in the appended claims. The invention itself, however, both as to structure and operation, together with additional objects and advantages thereof, will be best understood from the following detailed description of one embodiment thereof when read in conjunction with the accompanying drawings, in which:

Fig. 1 is a side elevational view, partly in section, of a circuit breaker embodying the principles of the invention;

Fig. 2 is a fragmentary sectional view taken on line II—II of Fig. 1 showing the structural features of a portion of the magnetic structure of the trip electromagnet.

Fig. 3 is a front elevational view of the circuit breaker.

Fig. 4 is a fragmentary elevational view, partly in section, of the breaker in the tripped open position.

Fig. 5 is a detail sectional view taken on line V—V of Fig. 1 showing the details of construction and mounting of the parts on the contact arm support shaft;

Fig. 6 is a sectional view taken on line VI—VI of Fig. 1 showing the construction and mounting of the holding coil.

Referring to Figs. 1 and 3 of the drawings, the circuit breaker includes a separable contact structure indicated generally at 11, an operating mechanism indicated generally by the reference character 13, a trip device 15, an arc blow-out magnet 17 and an arc chute indicated generally at 19.

The several elements comprising the circuit breaker are mounted on a framework comprising a pair of spaced upright support bars 21 of insulating material. The bars 21 are rigidly connected at their lower ends by an angle cross member 23 and a cross bar 25 disposed across the opposite edges of the bars 21 from the vertical portion of the angle bar. The cross mem-

ber 23 and the bar 25 are clamped tightly against the support members 21 by means of bolts 27 which are disposed on opposite sides of each of the support members in order to maintain the proper spaced relation between the upright support bars.

The upper ends of the support bars 21 are spaced apart and rigidly connected by means of a casting 29 having a portion 31 integral therewith and extending transversely of the support bars. The transverse portion of the casting 29 extends beyond the upright bars 21 and is rigidly clamped thereto by means of bolts 33 disposed on opposite sides of each of the support members 21 and which cooperate with a cross bar 35 and the portion 31 of the casting 29 to rigidly secure the casting 29 to the support member 21 and to space these members apart.

The operating mechanism 13 and the trip device 15 are supported in a frame comprising a pair of spaced parallel side plates 37 of magnetic material, which, at their left hand ends (Fig. 1), are rigidly clamped to the upright supports 21. The right hand ends (Fig. 1) of the side plates 37 are spaced apart and rigidly connected by an angular cross member 39 secured to the side plates 37 by means of screws 41. Referring to Fig. 6 it can be seen that the side plates 37 are clamped to their respective support members 21 by clamp plates 43 disposed on the opposite sides of the support members 21 from the plates 37, and securely held in place by bolts 45 and 47.

The plates 37 are supported at their right hand ends by an insulating block 49 (Fig. 1) which is in turn supported on a channel-shaped member 51, the block 49 being secured to the cross member 39 by screws 53 and to the channel member 51 by screws 55. A pair of spaced angle members 57 (Figs. 1 and 3) are suitably secured, for instance by welding, to the angle cross-member 23 and to the channel member 51, thus forming a rigid framework for supporting the operating mechanism. The entire framework is adapted to be supported on a suitable base (not shown).

The casting 29 mounted on the upper ends of the upright supports 21, has a vertically disposed plate 59 cast integral therewith and forming a mounting for the stationary contacts of the breaker. The stationary contacts comprise a main stationary contact member 61 and a stationary arcing contact 63. The main stationary contact 61 is mounted on a block 65 of conducting material which is slidably mounted on four stud bolts 67 (only two being shown) threadedly engaging the plate 59 and extending horizontally from the face thereof. Electrically connected to the back of the block 65, and mechanically secured thereto, is a pair of flexible shunt conductors 69 each comprising, preferably, a plurality of thin, flexible strips of conducting material. The flexible shunt conductors 69 are connected by means of bolts 71, to opposite sides of a conductor 73 which is, in turn, secured by means of screws 75 to a cross member 77 of the casting 29. A spring 79 compressed between the plate 59 and the flexible conductor 69 provides contact pressure for the main contacts when the breaker is closed. A spring guide 81 is provided on the plate 59 to retain the spring 79 in place.

The stationary arcing contact 63 is mounted on one end of a rod 83 slidably mounted in a sleeve 85 secured in the plate 59. The other end of the rod 83 is provided with a nut 87 to limit

the movement in one direction of the rod 83 and the contact. A spring 89 coiled about the sleeve 85 and compressed between the plate 59 and the arcing contact provides contact pressure for the arcing contacts. A flexible shunt conductor 90 connects the stationary arcing contact 63 to the main stationary contact 61.

The movable contacts comprise a main movable contact 91 and a movable arcing contact 93 (Figs. 1 and 4) carried on the upper end of a pivoted contact lever 95 pivotally mounted on a shaft 97 (Figs. 1, 3, 4 and 5) supported in the frame plates 37. The contact lever 95 comprises a pair of levers rigidly connected at their upper ends by an integral cross member 99 to which the arcing contact 93 is secured by means of screws 101. The main movable contact 91 is secured directly to the levers 95. The contact lever 95 is biased in a clockwise or opening direction by a pair of tension springs 103 (only one being shown) having one end hooked over a rod 105 mounted in the lower end of the contact lever and having their other ends anchored to spring studs 107 projecting from the plates 37. The contact lever 95 is also biased to open position by a pair of compression springs 109 threadedly mounted on screws 111 and supported on the bracket 39.

The contact lever 95 is releasably held in the closed contact position by a latch member 113 which is operated by the trip device 15 upon reversal of the direction of current flow in the circuit of the breaker, to release the contact lever and permit the springs 103 and 109 to operate it to the open contact position. The latch member 113 is rotatably mounted on a short tubular bearing 119 (Fig. 5) eccentrically surrounding the shaft 97 and supported in one end of a lever 121. The lever 121 comprises a pair of spaced levers pivoted on a pivot pin 123 mounted in the frame plates 37. At its other end the lever 121 carries an armature 125 pivotally supported on a pivot pin 127 mounted in the end of the lever 121. The armature 125 cooperates with an electromagnet 115 to retain the latch member 113 in latching position as shown in Fig. 1, and, as will be described later, the electromagnet operates upon the occurrence of reversal of current flow in the circuit of the breaker, to release the armature. As shown in Figs. 1 and 5, the internal diameter of the tubular bearing 119 is substantially larger than the outside diameter of the fixed pivot shaft 97. This permits the tubular bearing 119 and the latch 113 mounted thereon to move up and down relative to the axis of the fixed shaft 97. The tubular bearing 119 is disposed eccentric to the fixed shaft 97 in the closed position of the breaker so that this tubular bearing and the latch 113 mounted thereon can move downwardly upon release of the lever 121 by the tripping electromagnet.

A latch member 129 (Figs. 1 and 4) is adjustably secured by means of screws 131 to a cross bar 133 connecting the two levers 95 which form the contact lever. The force of the springs 103 and 109 tending to rotate the contact lever 95 clockwise, presses the lower beveled edge of the latch member 129 against the upper left hand corner of the latch member 113 and tends to move the latch member 113 in a clockwise direction about the tubular shaft 119. This rotation of the latch member 113 is normally prevented by means of a roller 135 mounted on a pin 137 supported in a closing lever 139. It will be noted that the beveled latch surface of the latch member

129 is inclined relatively to the longitudinal axis of the latch member 113. This results in a downward force on the latch member, which in turn produces an upward force in armature 125. Motion of armature 125 and therefore tripping of the latch member 113 is prevented by holding magnet 115 until reversal of current as will be described later.

The closing lever 139 is pivotally mounted on the shaft 97 (see Fig. 5) and is connected by 10 means of an adjustable link 141 to an operating lever 143 which is pivotally supported on a shaft 145 mounted in the frame plates 37. The upper end of the link 141 comprises an eye bolt 147 pivotally mounted on a pin 149 supported in the free end of the closing lever 139. The other end of the bolt 147 threadedly engages a yoke 151, the two legs of which are pivotally connected to the lever 143 by means of a pivot pin 153. A downwardly extending arm 155 of the lever 143 is pivotally connected to the upper end of a vertically disposed operating link 157, the lower end of which link may be connected to a power operated closing means (not shown). The link 141 and the lever 143 form a toggle which, in the 20 closed position (Fig. 1) is slightly overcenter to the left of the center line 149-145. In this position the force of the springs 103-109 transmitted through the contact lever 95, latch member 113, the closing lever 139 and link 141, biases the lever 143 in a counterclockwise direction against a stop screw 159 mounted in the angle member 39.

When the electromagnet 115 operates to release the armature 125, the springs 103-109 act to rotate the contact lever 95 clockwise to the open position (Fig. 4), and due to the beveled or inclined edge of the latch member 129 a component of the force of the springs causes the latch member 113 to move downwardly substantially radially relative to the shaft 97 rotating the lever 121 clockwise about its pivot 123. The latch 113 is thus disengaged from the latch piece 129 thereby releasing the contact lever 95 from the closing lever 139 whereupon the springs 103-109 quickly move the contact arm 95 to the open position shown in Fig. 4. The springs 109 are normally compressed between the member 39 and spring pads 110 (only one being shown) projecting laterally from the lower ends of the contact levers 95. The springs 109 serve to assist the springs 103 in moving the latch 113 to unlatching position and in starting the opening movement of the contact lever 95. The springs 103 complete the opening movement after the springs 109 have reached the limit of their expansion as can be seen in Fig. 4. It will be noted that the movable contacts and contact arm 95 are tripped free of the closing lever 139, i. e. the breaker will open when tripped even though the closing lever is held in closed position.

The shock of arresting the opening movement is dissipated by shock absorbers 112, there being a shock absorber secured to the inner face of each of the frame plates 37 engageable by the spring pads 110 as the contact lever 95 nears full open position. The shock absorbers may be of any suitable type preferably a spring biased plunger, or of any suitable resilient material.

As the contact lever 95 moves to open position the latch member 129 rides across the upper end of the latch member 113 holding the latch 113, the lever 121 and the armature 125 in their moved position (Fig. 4). During the tripping action of the latch 113, the closing lever 139 is 70 75

held in the position shown in Figs. 1 and 4 by the over-center condition of the toggle 141-143.

Referring particularly to Fig. 4, the contact lever 95 is rotated counterclockwise from its open position to the closed position by operation of the lever 143 which is accomplished by automatic closing means (not shown) but which moves the link 157 downwardly to close the contacts. Before the contacts may be closed, however, the closing lever 139 must be retrieved and relatched to the contact arm. The retrieving movement of the closing lever is effected by clockwise operation of the operating lever 143, the clockwise movement of the lever being limited by a stop 164 in the member 39.

The clockwise or retrieving operation of the lever 143 is automatically accomplished by means of a retrieving spring 166 (Fig. 1) having one end attached to the member 57 and the other end attached to the link 157. The spring 166 biases the link 157 upwardly and biases the lever 143 in a clockwise direction, however the tension of the spring 166 is not sufficient to move the toggle 141-143 overcenter against the force of the springs 103-109. When the latch 113 is moved downwardly to release the contact lever 95 the pressure of the springs 103-109 is no longer applied to the toggle 141-143 whereupon the spring 166 moves the link 157 upwardly and rotates the lever 143 clockwise until it is arrested by striking the stop 164. During the clockwise movement of the lever 143 the toggle 141-143 is moved overcenter to the right of the line 145-149 to a collapsed position thus 30 35 40 45 50 55 60 65 70 75 80 85 90 95 100 105 of the core members 167 is provided with a centrally located opening 177 (Fig. 2) through which passes a conductor comprising a pair of parallel conductors 179 forming a part of the electrical circuit of the breaker. At its left hand end the conductor 179 is mechanically and electrically connected by means of bolts 180 to the inner end of a terminal connector 181, and the right hand end (Figs. 1 and 4) of the conductor 179 is suitably connected, for instance by brazing to a yoke 183 (Figs. 1, 4 and 5) of conducting material. The yoke 183 has upwardly extending legs 185 (Fig. 5) each provided with an opening through which passes a sleeve 187 surrounding the shaft 97 (see Fig. 5) and having inner flanged ends disposed between the closing lever 189 and the legs 185. The legs 185 of the yoke 183 are disposed adjacent the inner sides of the contact levers 95 and are held in intimate contact with said levers by means of nuts 189 threaded onto the outer ends of the sleeves 187 and having spring washers 191 disposed between the outer faces of the levers and said nuts 189. Each of the nuts 189 is provided with a set screw 193 for locking the nuts in position after they have been rotated on the threaded portions of the sleeves 187 to provide the proper pressure contact between the legs 185 of the conductor yoke 183 and the contact levers 95.

The electrical circuit extends from the terminal connector 181 through the conductor 179, yoke 183, the legs 185 (Fig. 5) of the yoke, contact levers 95, the main contacts 91-91, flexible shunt conductors 69, conductors 73, through the coil 194 of the blow-out magnet 17 to a terminal connector 195.

As previously stated, the holding coil 117 (Figs. 1 and 6) is continuously energized from an independent source of energy and normally produces sufficient flux in the magnetic circuit to hold the armature 125 in attracted position. The holding coil 117 comprises a core member 197 (Fig. 6) of magnetic material having one end threaded as at 199 to receive a nut 201, also of magnetic material, and an energizing coil 203 surrounding the core member. After the coil 203 and the nut 201 are assembled on the core member 197, the assembly is inserted between the magnetic frame plates 37 adjacent the support bars 21 (Figs. 1 and 6) and a retaining bolt 205 is inserted through openings in the support bars 21, the frame plates 37 and the core member. The nut 201 is then rotated in a direction to force the end of the core member 197 and the nut into intimate contact with the adjacent frame plates 37. Nuts 207 on the threaded ends of the retaining bolt 205 are then tightened to retain the holding magnet assembly in place. It will thus be seen that the frame plates 37 form a part of the path for the magnetic flux of the holding magnet 117, the flux passing through the core member 197, one of the frame plates 37, the core members 167 and armature 125 of the magnet 115, and through the other frame member 37 back to the core member 197.

When the current is flowing in the proper direction in the circuit of the breaker including the conductor 179, the magnetic flux produced by the holding coil 117 in the magnetic circuit and through the core members 167 and armature 125 is in the same direction as the magnetic flux generated in the trip magnet 115 by the conductor 179. However, when the direction of current flow in the breaker circuit is reversed the magnetic flux of the trip magnet 115 produced by

the conductor 179 reverses its direction. The holding flux between the armature 125 and the magnet 115 is thus reduced to such a value that the armature is released and the springs 193-199 move the contact lever to open position.

The nut 87 on the left hand end of the arcing contact rod 83 (Fig. 1) is spaced slightly to the left of the portion 59 of the casting 29 in the closed position of the contacts so that when the contact lever 95 moves to open the contacts, the main contacts 61-91 will first separate and then, a very short time later, the arcing contacts 63-93 will open drawing the arc between the arcing contacts. The arc resulting from the flow of the current after the contacts have separated is drawn into the arc extinguisher 19 by means of the blow-out magnet 17 where it is extinguished. The blow-out magnet comprises the coil 194, connected in series relation in the circuit of the breaker, and a U-shaped core member 209 of magnetic material supported on the casting 29 and insulated from the coil 194. The legs of the core members 209 are supported by vertically disposed insulating bars 211 having their upper ends secured by means of screws 213 to the legs of the core member 209, the lower ends of the support bars 211 being supported on the frame plates 37 and secured thereto by screws 215.

The arc extinguisher is of the slotted plate type and the current of the arc drawn thereinto is shunted around the contacts and the breaker operating mechanism to the terminal connection 181 by means of a shunt circuit shown in part at 217 (Figs. 1, 3 and 6). This prevents the flow of current through the various pins, bolts and latches, which might damage them.

The arc extinguisher is preferably of the type fully disclosed and claimed in United States Patent No. 2,242,905, issued May 20, 1941, to R. C. Dickinson and R. H. Nau, and assigned to the assignee of the instant invention.

From the foregoing description it will be apparent that there is provided an improved circuit breaker of novel construction which is operated to open position at high speed in response to abnormal conditions and in which the contacts are trip free of the closing means. It will also be seen that the trip device comprises a holding magnet having a magnetic circuit which includes the frame members for supporting the breaker operating mechanism.

Having described the preferred embodiment of the invention in accordance with the patent statutes, it is to be understood that various changes and modifications may be made in the structural details disclosed without departing from some of the essential features of the invention. It is, therefore, desired that the language of the appended claims be given as reasonably broad interpretation as the prior art permits.

We claim as our invention:

1. In a circuit breaker, relatively movable contacts, a switch member mounted on a fixed pivot and movable to open and close said contacts, operating mechanism for said switch member including an operating member operable to effect closing movement of said switch member, a latch member having its free end interposed between the switch member and the operating member for connecting said switch member to said operating member, said latch being supported independently of said operating member and said switch member, a trip device including electro-responsive means normally restraining said latch in latching position and being operable in re-

sponse to predetermined circuit conditions to cause said latch to be moved to unlatching position to thereby effect opening of said contacts.

2. In a circuit breaker, relatively movable contacts, a switch member mounted on a fixed pivot and movable to open and close said contacts, operating mechanism for said switch member including an operating member movable to effect closing movement of said switch member, means interposed between said switch member and said operating member for releasably restraining said switch member in closed position, said means being supported independently of said members, a holding electromagnet structure for holding the restraining means in restraining position, said holding electromagnet being operable in response to predetermined circuit conditions to permit longitudinal movement of the restraining means to a non-restraining position to thereby permit opening movement of the switch member, and said restraining means being operable by said operating member to move the switch member to closed position.

3. A circuit breaker comprising relatively movable contacts, a switch member movable to an open and to a closed position to open and close said contacts, operating mechanism for said switch member including a member pivoted coaxially with said switch member operable to effect closing movement of the switch member, means for restraining said operating member in closed position, a member supported independently of said operating member and extending between the switch member and the operating member for normally connecting the switch member to said operating member, and a holding magnet for holding said connecting member in connecting position, said holding magnet being operable in response to predetermined circuit conditions to permit movement of said connecting member from between the switch member and said operating member to permit opening movement of the switch member irrespective of the position of the operating member.

4. A circuit breaker comprising relatively movable contacts, a switch member pivoted on a fixed pivot biased to open position and operable to open and close said contacts, operating mechanism for said switch member including a lever movable to effect closing operation of said switch member, a latch member supported separately from said switch member and said operating lever and extending between said lever and said member for releasably connecting the switch member to the operating lever, said latch being biased to unlatching position, means including an electromagnet for holding said latch member in latching position, said holding electromagnet being operable in response to predetermined circuit conditions to permit movement of said latch member to unlatching position to effect opening movement of the switch member.

5. A circuit breaker comprising relatively movable contacts, a switch member biased to open position and movable to open and close said contacts, operating mechanism for said contacts including a member operable to effect closing of said contacts, a pivotally and longitudinally movable latch member having its free end disposed between the switch member and said operating member for releasably connecting said switch member and said operating member, means operable in response to predetermined circuit conditions to cause withdrawal of the latch member

to effect opening movement of said switch member.

6. A circuit breaker comprising relatively movable contacts, a switch member movable to open and close said contacts, operating mechanism for said switch member including a lever for operating said switch member to closed position, a latch member connecting the switch member to the operating lever to releasably restrain said switch member in closed position, means for pivotally supporting said latch member, said support means being operable in response to reversal of current in the circuit to effect longitudinal movement of said latch member to release said switch member, and said latch member being pivotally movable with said operating lever to effect closing movement of said switch arm.

7. A circuit breaker comprising relatively movable contacts, a pivoted switch arm movable to open and close said contacts, operating mechanism for said switch arm including an operating lever pivoted coaxially with said switch arm and operable to effect movement of said switch arm to closed position, a movable latch having an end interposed between said switch arm and said operating lever to releasably connect said switch arm and said operating lever, means independent of said switch arm and said operating lever for supporting said latch for longitudinal movement to an unlatching position means biasing said switch arm to open position and biasing said latch to unlatching position, and a holding magnet for holding said latch in latching position and operable in response to reversal of current in the circuit to permit said biasing means to move said latch to unlatching position and to move said switch arm to open position.

8. A circuit breaker comprising relatively movable contacts, a switch arm biased to open position and movable to open and close said contacts, an operating member, a pivoted latch having its free end normally interposed between said switch arm and said operating member for restraining said switch arm in closed position, means supporting said latch independently of said switch arm and said operating member, a holding magnet for holding said latch in restraining position, said holding magnet being operable in response to predetermined circuit conditions to release said latch, means on said switch arm for moving said latch longitudinally from its position between said switch arm and said operating member, means to operate said operating member to effect pivotal resetting movement of the latch, said holding electromagnetic means actuating said latch to its position between said switch arm and said operating member while said switch arm is in open position.

9. A circuit breaker comprising relatively movable contacts, operating means therefor, a member interposed between the operating means and the movable contact to restrain said movable contact in closed position, a frame for supporting said operating means, a trip device including a trip member for pivotally supporting said restraining member, and electromagnetic means for holding said restraining member in restraining position and operable in response to predetermined circuit conditions to permit longitudinal movement of said restraining member from between said operating means and said movable contact, said supporting frame forming a part of said electromagnetic means.

10. In a circuit breaker comprising a supporting frame for supporting the breaker mechanism,

relatively movable contacts and operating mechanism for said contacts, a trip device including a latch member connecting the movable contact and said operating mechanism for restraining said movable contact in closed position, a trip member for pivotally supporting said latch member and operable to permit longitudinal movement of said latch member to a non-restraining position, and electromagnetic means including said supporting frame for holding said trip member against tripping movement, said electromagnetic means being responsive to predetermined circuit conditions to release said trip member.

11. In a circuit breaker including spaced supporting frames of magnetic material for supporting the breaker mechanism, a trip device including a latch member operable to effect opening of the breaker, a trip member for pivotally supporting said latch member and operable to actuate said latch in a longitudinal direction to a non-latching position, an electromagnet for holding said trip member against tripping movement and operable in response to reversal of current in the circuit to release said trip member, said electromagnetic having a magnet core mounted between said spaced supporting frames, and a holding electromagnet having a core member mounted between said spaced supporting frames for energizing said first named electromagnet, said supporting frames forming a part of the magnetic circuit for said holding electromagnet.

12. In a circuit breaker, the combination of relatively movable contacts, a pivoted switch member biased to open position and movable to open and close the contacts, an operating member pivoted coaxially with said switch member and operable to effect movement of said switch member to closed position, a latch connecting the switch member and said operating member to releasably restrain said switch member in closed position, a trip member for supporting said latch for pivotal and longitudinal movement relative to said switch member, and an electromagnet for holding said trip member and said latch in restraining position, said holding electromagnet being operable upon reversal of current in the circuit of the breaker to permit longitudinal movement of said latch to effect opening movement of the switch member.

13. In a circuit breaker, the combination of a pivoted switch member movable to open and closed positions, operating mechanism for said switch member including a lever pivoted coaxially with said switch member and operable to move said switch member to closed position, a trip device including a trip lever, a latch member pivotally supported on said trip lever and having one end interposed between said switch member and said lever for normally connecting said switch member and said operating lever to restrain said switch member in closed position, and a holding electromagnet including an armature carried by said trip lever for holding said latch in connecting position, said holding electromagnet being operable in response to reversal of current in the circuit of the breaker to release said armature and permit longitudinal movement of said latch to release the switch member.

14. In a circuit breaker, the combination of relatively movable contacts, a pivoted switch arm movable to open and close said contacts, an operating member pivoted coaxially with said switch arm and operable to move said switch arm to close the contacts, a latch pivoted eccentrically of said switch arm and said operating member

for normally connecting said switch arm and said operating member, a trip member supporting said latch for rotary and substantially radial movement relative to the pivot of said switch arm and said operating member, and electro-responsive means operable in response to predetermined circuit conditions to effect radial movement of said latch to disconnect said switch arm from said operating member irrespective of the position of said operating member.

15. A circuit breaker comprising relatively movable contacts, a switch member movable to open and close said contacts, operating mechanism for said switch member including a member operable to effect movement of said switch member to closed position, a latch member having one of its ends interposed between said switch member and said operating member to releasably connect said switch member and said operating member, biasing means at all times biasing said switch member to open position, auxiliary biasing means for biasing said switch member in opening direction during at least a portion of the opening stroke, and a holding magnet for restraining said latch in latching position and operable to permit said biasing means to move the latch longitudinally to unlatching position and to move said switch member to open position.

16. A circuit breaker comprising relatively movable contacts, a switch member movable to open and close said contacts, operating mechanism for said switch member including a member operable to effect movement of said switch member to closed position, a latch member interposed between said switch member and said operating member to releasably connect said switch member and said operating member, spring means biasing said switch member in opening direction and biasing said latch to unlatching position, 40 said spring means being operable to move said switch arm to full open position, auxiliary spring means biasing said switch member in opening direction and biasing said latch in unlatching direction at least during the unlatching portion of the opening movement of said switch member, and a holding magnet for holding said latch in latching position and operable to permit said biasing means to move said latch to unlatching position and to move the switch member to open position.

17. A circuit breaker comprising relatively movable contacts, a switch member movable to open and close said contacts, operating mechanism for said switch member including a member operable to effect closing movement of said switch member, means interposed between the switch member and said operating member for releasably restraining said switch member in closed position, means biasing said switch member to open position, said biasing means acting through said switch member to bias said restraining means to a non-restraining position, and a holding magnet for holding said restraining means in restraining position and operable to permit said biasing means to move said restraining means to non-restraining position and to move said switch member to open position, a part of said biasing means being effective to bias said switch member to open position only during a portion of the opening movement of said switch member.

18. In a circuit breaker, the combination of a pivoted switch member movable to open and closed positions, means biasing said switch member to open position, operating mechanism for

13

said switch member including a lever pivoted coaxially with said switch member and operable to move said switch member to closed position, a trip device including a tripping lever pivoted at a point spaced from the axis of rotation of said closing lever, a latch rotatably mounted on said tripping lever about an axis adjacent the axis of said operating lever, means connecting said latch for movement with said operating lever, a latch element on said switch member engageable by said latch to connect said switch member and said operating lever, the engaging surfaces of said latch element and said latch being disposed so

5

10

14

that the opening force on said switch member tends to move said latch and tripping lever to released position to release said switch member from said operating lever, and magnetic means for normally holding said tripping lever and latch in latching position, said magnetic means being operable in response to predetermined abnormal conditions to permit said latch and tripping lever to move to released position.
